Primary Examiner — Kendra Leslie Hamilton(74) *Attorney, Agent, or Firm* — Aileen Law; Oppedahl Patent Law Firm LLC(57) **CLAIM**

The ornamental design for a spur for bull riding, as shown and described.

DESCRIPTION

FIG. 1 is a top, front, left, perspective view of a spur for bull riding, showing our new design;

FIG. 2 is a top, front, right, perspective view thereof;

FIG. 3 is a top, back, right, perspective view thereof;

FIG. 4 is a top, back, left, perspective view thereof;

FIG. 5 is a bottom, front, left perspective view thereof;

FIG. 6 is a front elevation view thereof;

FIG. 7 is a back elevation view thereof;

FIG. 8 is a left side elevation view thereof;

FIG. 9 is a right side elevation view thereof;

FIG. 10 is a top plan view thereof; and,

FIG. 11 is a bottom view thereof.

The claim also includes a second embodiment of the spur for bull riding that is a mirror image of FIGS. 1-11.

The broken lines in the figures form no part of the claimed design.

1 Claim, 11 Drawing Sheets(56)
